(54) **MOTION, CHANGING**

(76) Inventor: **Otis Pettee**

His Letters
Patent.

The Schedule referred to in these Letters Patent and, making part of the same containing a description in the words of the said Mr. Pelle himself, of his improvement in changing the motion of machinery.

Be it known that the said Mr. Pelle have invented constructed and applied to use a new and useful improvement for producing any required change in the velocity of machinery while in motion. In relating the description of the said invention and the manner of using the same.

I take two cylinders of iron or other metal placing the same parallel to each other at a convenient distance apart. One of the cylinders has a uniform rotary motion communicated to it by means of a wheel placed at either end. This is, from be fixed upon this cylinder a series of cog wheels contiguous to one another of various sizes. There is also placed upon the other cylinder a series of cog wheels contiguous to one another and bearing such a proportion to the former series as that being constantly in contact with the former they communicate to each of the latter a certain required velocity. The latter wheels are not fixed but receive separately, on the cylinder, as on an axis. The object now is to make the cylinder at step first turn the inner cog series of velocity with which the outer wheel, in place upon it moves. This object is effected by fastening firmly upon the cylinder one of the wheels, at a time, and then loosing up, it and immediately fixing the wheel contiguous to the different wheel, thus communicating successively to the cylinder their several velocities. These wheels are each, for a given moment, immovable in the following manner. In cylinder on which they are placed there is a hole through which is passed a small iron pin or needle. The wooden frame of an armchair which is made to slide easily within the cylinder, on one side of this frame, is placed a spring with a notched end, so arranged as a slot or groove made through the side of the cylinder. The catch is moving a little without the cylinder. The inner surface of each of the several wheels is notched so that when the slide is moved the catch goes into

a notch on one of the wheels and this fixes the wheel firmly to the cylinder. It is found convenient to have two separate springs, each fixed to the iron frame containing it, each other, so that if one of them should not strike a notch the other will. The cylinder frame above described is moved by means of a screw neck to which it is attached with a screw, so as to allow the slide to move when the screw turns, at rest. On the upper side of the neck there is a number of teeth equal to half the number of teeth in the end of the neck, so that the distance between the several teeth twice the thickness of one of the wheels. These teeth are placed alternately, so that the slide may run over them, one of which is placed forward of the other. The thickness of the neck is such that when one is passing over a tooth, the other is about to come into next. The time of the motion of these steps is accurately regulated, so as to allow the cylinder to move with an evenness during its motion. When the velocity is to be changed the hammer which lifts the neck which rises and the neck is thrown out. The block weight of the wheel, when it is stopped again by the other hammer. The neck is removed by means of a chisel and weight. Then all the movable parts have been released when the neck is set back by means of a pinion working against the teeth on the underside of the neck and turned inwards. The cylinder part attached turns when the cylinder is turned inwards, the cylinder part turning on its circumference. From a great variety of chances it is found it is best that the first cylinder should be hollow to render it less liable to break. The manner above described of raising and releasing the wheel is that which I have applied to use. For the same effect may be produced by having the cylinder a wheel, these wheels are attached with and the cylinder moving in a groove in the side of the cylinder. The slide in this case being a pin, which is fastened with a spring or catch at one end which is to face the wheel when the cylinder is in the other case. The groove being the other end of the cylinder and sufficiently deep to admit the slide to move freely in it while the cylinder is turning. The outer end of the

slide should be bent at right angles so as to come in a line with the axis of the cylinder, and is fastened to the rack and pinion when it is in the other case. The outer slide, the slide may have a curve so that it may be convenient to have the groove in the cylinder opposite each other, and two slides meeting in them take the place of a pair of slides. The pins being on a single slide so arranged that if one of them stops, not striking a notch in the wheel in other will stop the other. The invention is used. It is considered, the principle the same in each which consists in producing any desired change in the velocity of motion of a wheel in motion by means of a series of any wheels, moving with the different velocities and rotating upon a cylinder, as upon an axis, and being successively passed and disengaged when required by means of a sliding gear which passes into notches cut into the inner surfaces of the wheels. These wheels, receiving this motion from another series of wheels, attached firmly to another cylinder which moves with an uniform velocity and the slide being moved on and off a rack with which it is connected and upon which it moves. The machinery in question this above invention has been applied to use in a cotton spinner for rolling cotton, but it can in the same way be used in the same as well in this spinning time machinery.

I do testify that the above is a true specification and description of my said invention. I have here set my hand and seal the third day of February in the year of our Lord one thousand eight hundred and twenty five.

DEPARTMENT OF THE INTERIOR,

United States Patent Office,

Washington, D. C., 189...

SIR:

The printed *C. A. F. C.* of Patent No. *6,125*
is now exhausted.

As soon as printed a copy will be mailed you to complete your order.

By direction of the Commissioner:

Very respectfully,

Chief Clerk.
